CLAIM

The ornamental design for a combined moulded rotary knob and nut, as shown and described.

DESCRIPTION

FIG. 1 is a perspective view in the assembled position of a combined moulded rotary knob and nut showing my new design; and,

FIG. 2 is a perspective view in the separated position of the combined moulded rotary knob and nut shown in FIG. 1.

The side of the design opposite that shown in FIG. 1 is identical except for the omission of the pointer and the bottom is unornamented.

FIG. 1

FIG.2

UNITED STATES PATENT AND TRADEMARK OFFICE
CERTIFICATE OF CORRECTION

PATENT NO. : Des. 344,440
DATED : February 22, 1994
INVENTOR(S) : John M. Oakley

It is certified that error appears in the above-identified patent and that said Letters Patent is hereby corrected as shown below:

On the Title Page delete "Filed: July 12, 1991" and insert --Filed:
August 12, 1991. --

Signed and Sealed this
Twenty-third Day of August, 1994

Attest:
